UNITED STATES PATENT OFFICE.

ERASMUS BENNETT, OF TOPEKA, KANSAS.

COMBINED LIFE-PRESERVER AND MAGAZINE.

SPECIFICATION forming part of Letters Patent No. 535,045, dated March 5, 1895.

Application filed March 31, 1894. Serial No. 505,875. (No model.)

To all whom it may concern:

Be it known that I, ERASMUS BENNETT, a citizen of the United States, residing at Topeka, in the county of Shawnee and State of Kansas, have invented certain new and useful Improvements in a Combined Life-Preserver and Magazine; and I do declare the following to be a full, clear, and exact description of the invention, such as will enable others skilled in the art to which it appertains to make and use the same, reference being had to the accompanying drawings, and to the letters and numerals of reference marked thereon, which form a part of this specification.

My invention relates to devices for the protection and defense of persons who may at any time or place be in danger from the attacks of burglars, robbers, pirates, &c., while guarding treasures, whether upon a car or other moving vehicle; or stationary in some apartment in a building, or wherever a treasure may be located and there is danger to life through an attack made upon the person guarding or watching said treasure; and my improvements consist in placing a shield, having a port hole and side entrance and capable of being revolved, within a stationary shield having a series of port holes so arranged that the port hole of the revolving shield may be brought into line or made to register with any one of the port holes in said series.

Figure 1 is a view in elevation of my invention as secured to the inside of a car body (shown in section) at one corner thereof. Fig. 2 is an isometrical view in elevation of my invention detached. Fig. 3 is a vertical section through Fig. 2, centrally of the registered port holes. Fig. 4 is a view in elevation of the inner shield.

An outer stationary shield A, is provided with a series of peripherally arranged port holes a, and side entrance or opening B, and conical or pointed top and bottom, or upper and lower end pieces. The lower end piece b, is provided with a flooring which has a socket c, and is filled with wood pulp, fibrous material or any material that will give it the necessary strength or cause it to resist the force of explosives, such as powder, dynamite, &c. The upper end c' is provided with a socket e, and openings f. Door B' is made to close entrance B.

An inner or magazine shield C, is provided with a side opening or entrance D, door E, and port hole g. A pivot pin h, is secured to 55 a cross-piece i', at the bottom, and at top is a similar pin j, also openings k. Pins h and j, enter corresponding sockets c and e in outer shield.

The cross-piece i, is secured centrally to the 60 bottom of the inner shield, thus leaving the bottom open on both sides thereof so that the watchman may, if desired, transfer his weight through these openings to the floor of the outer shield. The under central portion of 65 the cross-piece is extended downward slightly (as shown in Figs. 3 and 4) to which extended portion the pin h, is secured and upon which the weight of the inner cylinder is brought to bear, leaving an unobstructed space, else- 70 where, between the floor of the outer shield and the bottom of the inner one.

The inner shield may be provided with ammunition, guns, pistols, &c.

Bands 1, and 2, secured to the outer shield 75 by rivets or otherwise are made to hold the invention in place (within a car body) by bolting, or otherwise securing said bands to the car body. See Fig. 1. Although I have shown my invention located within and secured to a car body at one corner, it may be located at any other desired point within the car body or so located as to be partly within and partly without so that a person within the shield or shields may inspect both the in- 85 side and outside of the car. The outer shield may be provided with suitable standards so as to be capable of being set up anywhere within an apartment, or at any desired place within a bank or vault, or any other place 90 whatever, where valuables are kept and where the person watching or guarding the same is in danger of losing his life or being injured through an attack upon him by robbers, &c.

Although I have shown my invention as 95 composed of an outer and inner shield—two concentric cylinders—this form may be departed from somewhat to suit place and surroundings. The outer shield with its upper and lower ends pointed, serves to prevent a 100 cartridge of explosive material being readily applied to the top, and this formation also serves to break the force of an explosion whether at top or bottom.

Ventilation is provided for through the openings *f* and *h*, and the port-holes.

The shields are to be made of iron (boiler iron) or other suitable bullet-proof material.

5 The doors *B'* and *E* may be provided with suitable locks or bolts.

A person in danger may pass into the inner or magazine shield and standing upon the floor of the outer shield may turn, by hand, the 10 inner or magazine shield until its port-hole registers with any desired port-hole in the outer shield, when the two shields are used in combination. By this arrangement it will be seen that a watchman within the inner shield 15 can thoroughly protect himself against any missiles coming through any of the port-holes in the outer shield by turning the inner one so that its port-hole will be in a line midway of any two port-holes in the outer shield; and 20 that he is always protected in his rear when looking out or defending himself.

Having thus described my invention, what I claim therein as new, and desire to secure by Letters Patent, is—

25 1. The combination of an outer stationary

shield, having a side entrance and a series of port-holes, with an inner revolving shield having a side entrance and a port-hole so arranged that upon the rotation of the inner shield said port hole will register with any desired port-hole in the outer shield. 30

2. The outer stationary shield having a side entrance, a series of peripherally arranged port-holes and the conical or pointed end pieces—the lower one of which is filled with 35 fibrous material—in combination with the inner revolving shield having a port-hole and side entrance, substantially as described.

3. A shield having its top and bottom pointed, a series of port holes and side entrance, in combination with a rotary inner shield having a port-hole, side entrance and openings at bottom, substantially as described. 40

In testimony whereof I affix my signature 45
in presence of two witnesses.

ERASMUS BENNETT.
